UNITED STATES PATENT OFFICE

148,895

DESIGN FOR AN EARRING RACK

Portia L. Trenholm, Montgomery, Ala.

Application December 6, 1946, Serial No. 135,303

Term of patent 7 years

(Cl. D80—9)

To all whom it may concern:

Be it known that I, Portia L. Trenholm, a citizen of the United States of America, residing at Montgomery, in the county of Montgomery and State of Alabama, have invented a new, original, and ornamental Design for an Earring Rack, of which the following is a specification, reference being had to the accompanying drawing, forming a part thereof.

In the drawing:

Figure 1 is a front elevational view of the earring rack embodying my new design.

Figure 2 is a top plan view of the rack shown in Figure 1.

I claim:

The ornamental design for an earring rack, as shown.

POR TIA L. TREN HOLM.
